(57) **CLAIM**

The ornamental design for a hydro foil for a surfboard, as shown and described.

DESCRIPTION

FIG. 1 is a perspective view of a hydro foil for a surfboard showing my new design;

FIG. 2 is a front view thereof;

FIG. 3 is a rear view thereof;

FIG. 4 is a side view thereof, the opposite side being identical thereto;

FIG. 5 is a top plan view thereof;

FIG. 6 is a bottom plan thereof; and,

FIG. 7 is a cross-sectional view taken along lines 7—7 of FIG. 5.

The broken lines in the drawing are for illustrative purposes only and form no part of the claimed design.
